UNITED STATES PATENT OFFICE.

JAMES FRANKLIN WADDINGTON, OF BEVERLY, NEW JERSEY.

SHIP-DAVIT.

1,297,276.

Specification of Letters Patent. Patented Mar. 11, 1919.

Application filed January 12, 1918. Serial No. 211,594.

To all whom it may concern:

Be it known that I, JAMES FRANKLIN WADDINGTON, a subject of the King of England, residing at Perkins Lane, Beverly, in 5 the county of Burlington and State of New Jersey, have invented new and useful Improvements in Ship-Davits, of which the following is a specification.

The invention relates to boats and more 10 particularly to raising and lowering devices for ships, and has for an object to provide davits for conveniently supporting life boats or other life-saving paraphernalia on or adjacent to the deck or side of the ship, where 15 the same will be out of the way when not in use, and capable of being readily and effectively moved into position for use for raising or lowering life-saving boats or other devices. 20 Among other features, the invention comprehends the provision of davits which will not only support the life boat or the like in an out-of-the-way position when the same is not in use and permit of swinging the life 25 boat into position where it can be conveniently and quickly lowered, but the operation of moving the life boat from its normal position to the place or spot where it is to be lowered alongside of the ship is one that 30 can be quickly and effectively accomplished, with a minimum amount of work and labor, and with the assurance that there will be no hitch in the operation, so that in an emergency, or otherwise, the desired operation can 35 be accomplished without mishap.

I am aware that various forms of ship davits have been used heretofore and are in use at the present time, and with these in mind I have produced ship davits which will 40 accomplish the result for which they are intended much more effectively and with less labor. Furthermore, I aim to provide ship davits which can be more cheaply constructed and more readily assembled and 45 placed in position for use, than some other forms of known ship davits.

In the further disclosure of the invention reference is to be had to the accompanying drawing, constituting a part of this 50 specification, in which similar characters of

reference denote corresponding parts in all the views, and in which—

Figure 1 is a fragmentary end view showing a life boat supported by my form of davits, on the deck of a ship, the full lines 55 indicating the normal position of the boat and davits, and the dotted lines the position of the boat and davits when the same are swung outward beyond the side of the vessel.

Fig. 2 is a fragmentary side elevation with 60 parts in section, showing the arrangement of the davits and the bracing therefor, the operating mechanism of this view being removed.

Fig. 3 is a substantially horizontal sectional view, slightly enlarged, taken on the line 3—3 of Fig. 1, and 65

Fig. 4 is a longitudinal sectional view taken on the line 4—4 of Fig. 1, the view being slightly enlarged. 70

Referring more particularly to the views, the numeral 10 indicates the deck of a vessel 11 and the numeral 12 a side of the vessel, while the numeral 13 indicates one of the uprights or main elements of the 75 davits, it being understood that a plurality of these uprights is of course employed, although a single-operating mechanism is preferably used. For this reason I will describe merely one of the uprights and the 80 single-operating mechanism used in conjunction therewith.

Secured to the deck 10 is a base 14 which may be of channel or other convenient form of construction, with the upright 13 mounted to swing upon an end of the base, the upright being slightly inclined, as shown in Fig. 2. A slightly inclined rod or shaft 15 forms part of the pivotal connection of the upright 13 with the base, and an end of said 85 rod is journaled in a supplemental base or anchor plate 16, a suitable brace or tie rod 17 being also connected to the anchor plate 16, and projecting upwardly at an angle toward the upright 13 to be rigidly connected 90 to the upper end thereof, the upper end of the tie rod being formed to provide a suitable hook 18 which projects and depends to one side of the inner face of the upright, and to which is suitably connected the usual 100

block 19 employed in raising or lowering ships, said block having ropes 20 passing thereover, and which also pass over a block 21 suitably connected to the life boat 22, it being understood by manipulating the ropes 20, the life boat 22 can be raised or lowered as desired.

Pivoted on the other end of the base 14 is a link 23 which in detail is shown in Fig. 4, 10 and which may consist of a channel section or other convenient form of construction, the upper end of said link 23 having hinged connection with a tubular crosshead 24, internally threaded to operate over a screw 25 15 which is pivoted on the base 14 and extends upwardly at an angle and at one end thereof has an operating wheel 26. The link 23, together with the screw 25, its operating wheel 26 and the crosshead 24, form a part of the 20 operating mechanism, and the latter is completed by the provision of a second link 27 having pivotal connection with the crosshead, and which extends upwardly and forwardly for hinged connection with a plate 25 28 rigidly secured to the upright 13.

As mentioned heretofore, the upright 13 is inclined toward the space which is occupied by the life boat, and so also the brace or tie rod 17, this form of design being desired so 30 as to provide absolutely swinging clearance for the life boat between the uprights and the davits, and referring to Fig. 2 it will be seen that normally the upright 13 is inclined inwardly toward the center of the ship or 35 vessel on which the davits are arranged, the crosshead 24 at this time being in its uppermost position of the screw and abutting against the operating wheel 26. With this arrangement it will be seen that the life 40 boat 22 lies wholly within the vertical plane of the side 12 of the vessel, and the life boat therefore is supported above the deck of the vessel, and does not project over the side where it might be an obstruction to the 45 proper navigation of the vessel.

When it is desired to lower the life boat or swing the life boat into position where it will be conveniently ready to lower to the sea, it is only necessary to manipulate the 50 operating wheel 26, causing the screw 25 to turn and thus advance the crosshead along the screw toward its lower end. This will cause the two links 23 and 27 to act and the result will be the swinging of the upright 55 13 from its normal position, shown in full lines of Fig. 1, to an outward position, shown in dotted lines of the same figure, so that the life boat will assume a position adjacent to and free from the side of the vessel, 60 this position being clearly shown in Fig. 1.

It will also be clear that in raising the life boat from the sea and the deck of the ship, the reverse of the operation heretofore described, takes place, and the reversal of

the operation of the screw will swing the uprights of the davits back into normal position, thus bringing the boat over the deck of the vessel.

It will of course be understood that I do not limit myself to the particular form of 70 device shown and described; that various slight changes may be made without departing from the spirit of the invention; that the device may also be used for other desirable purposes than for use with life boats or life 75 rafts, and the scope of the invention is defined in the appended claims.

I claim:

1. In a device of the character described, the combination with a base, of uprights 80 mounted to swing on the base and normally inclined toward an inward position, said uprights being adapted to support a boat therebetween, tie rods for said uprights to swing therewith to hold said uprights inclined toward said boat, a revoluble screw, an operating wheel therefor, an element in threaded engagement with the screw to be advanced or retreated thereon, and links, having pivotal connection with said element, one of 90 said links connecting with one of the uprights and the other link with the base, whereby when said screw is operated, said upright will be swung from its normal inwardly inclined position to an outwardly inclined position, or vice versa.

2. In a device of the character described, the combination with a base, of uprights mounted to swing on the base and normally inclined toward an inward position, said uprights being adapted to support a boat therebetween, a revoluble screw, an operating wheel therefor, an element in threaded engagement with the screw to be advanced or retreated thereon, and links, having pivotal 100 connection with said element, one of said links connecting with one of the uprights and the other link with the base, whereby when said screw is operated, said upright 105 will be swung from its normal inwardly inclined position to an outwardly inclined position, or vice versa.

3. In a device of the character described, the combination with a base, of supporting uprights mounted to swing on the base to 115 support an object, such as a boat, said uprights being normally in an inclined inward position and at all times inclined toward the object, to permit of the object swinging freely therebetween, a revoluble screw, 120 means for operating said screw, an element in threaded engagement with the screw to be advanced or retreated thereon, and links, having pivotal connection with said element, one of said links having pivotal connection 125 with the base, and the other link having pivotal connection with one of the uprights, whereby operation of the screw will swing

said uprights from their normal inwardly inclined position, into an outwardly inclined position and carry said boat therewith.

4. In a ship's davits, the combination with
5 a boat-supporting swinging upright normally supporting the boat above the deck of the ship, with said upright normally inclined inwardly toward the ship, and inclined toward the boat to permit of the boat always

swinging clear of the upright, a tie rod 10 mounted to swing with the upright and hold the said upright inclined toward the said boat, and means for swinging the upright outwardly into an inclined position to carry the boat adjacent to and clear of the side of 15 the ship, or vice versa.

In testimony whereof I affix my signature.
JAMES FRANKLIN WADDINGTON.
